MERCHANDISER FOR FOOD AND THE LIKE

Eugene Buday, Wilkins Township, Allegheny County, Pa.
(324 Sunset Drive, Pittsburgh, Pa. 15235), and Sol
Blackman, 1152 Towanda Terrace, Cincinnati, Ohio
45216

Filed Dec. 6, 1974, Ser. No. 530,441

Term of patent 7 years

Int. Cl. D6—04; D20—02
U.S. Cl. D6—168

FIG 1

FIG 3

FIG. 6
FIG. 5
FIG. 4

FIG. 1 is an enlarged perspective view of a merchandiser for food and the like showing our new design;

FIG. 2 is a top plan view thereof;

FIG. 3 is a bottom plan view thereof;

FIG. 4 is a front elevational view thereof;

FIG. 5 is a side elevational view thereof, the opposite side being identical;

FIG. 6 is a rear elevational view thereof.

We claim:

The ornamental design for a merchandiser for food and the like, as shown and described.
